UNITED STATES PATENT OFFICE.

CONSTANTY MAJEWICZ, OF DETROIT, MICHIGAN.

SOUNDING DEVICE FOR TOY ANIMAL FIGURES.

Application filed December 13, 1926. Serial No. 154,461.

This invention relates to toys and particularly relates to toy animal figures.

It is an object of the invention to provide means within a toy animal figure for simulating the sounds produced by an animal of the type represented by said figure.

More specifically it is an object of the invention to arrange within a toy figure representing a dog, means for simulating the barking of a dog.

Another object is to provide means readily operable by a child for operating sound-producing mechanism disposed within a toy animal figure.

These and various other objects the invention attains by the construction herein-after described and illustrated in the accompanying drawings; wherein:

Figure 1 is a perspective view of a sound-producing device adapted to be arranged within the body of a toy animal figure.

Figure 2 is a view in side elevation of a toy animal figure, showing in dash lines the device of Figure 1 installed in said figure and showing a means for operating said device by propelling the dog forwardly or rearwardly.

Figure 3 is a plan view partly in section of an animal figure and of a sound-producing device therein, operable by pressure applied to the body of said figure.

In these views, the reference character 1 designates a hollow toy figure representing a dog, which figure may be papier mâché, sheet metal, or other suitable material.

Within the body of said figure is installed a sound-producing device comprising a platform or base 2, a flexible plate 3 resting edgewise upon a rosin-treated end portion of the top face of said base, an arm 4 one end of which carries the plate 3, and a pitman member 5 connecting the other end of said arm to the crank 6 of a shaft 7. Said shaft is preferably journaled in a U-shape bracket 8 mounted fast upon the other end portion of said base. Said bracket may be conveniently formed as a sheet metal stamping. Turning of the crank-shaft 7 acts through the pitman 5 to reciprocate the arm 4 and to thus

slide the plate 3 back and forth on the rosin-treated surface of the base, and the resulting vibration the lower edge of said plate against said surface is productive of a sound somewhat resembling the barking of a dog.

It is preferred to mount fast upon the mid portion of the base a block 9 formed of

wood or other suitable material upon which rests the actuated end portions of the arm. Said block thus serves as a guide for the arm and by maintaining said arm substantially parallel to the base, also maintains the desired perpendicular relation of the plate 3 to the base.

It is further preferred to arrange between the plate 3 and block 9 a coiled spring 10 extending under a slight tension between the base 2 and arm 4, and establishing a slight pressure of the plate 3 upon the base. This increases somewhat the frictional resistance offered by the rosin surface of the base to reciprocation of the plate and adds to the volume of the resulting sound.

The shaft 7 extends out through the body of the Figure 1 and carries a suitable actuating element or elements exteriorly of said body. Thus, as is illustrated in Figure 2, the ends of said shaft may carry a suitable pair of wheels 11 proportioned to engage the surface supporting the toy figure, so that said wheels will turn said shaft as the figure is propelled forwardly or back upon said surface.

In that form of the invention which is illustrated in Figure 3, either the entire animal figure 12 or a suitable portion thereof is formed of rubber or like resilient material. The base 2', slide 3' and arm 4' conform to the description already given. For actuating the arm, this construction employs a pair of divergent fingers 13, having their adjacent ends connected to the rear ends of said arm by a common pivot member 14.

Between the diverged ends of said fingers, a block 15 is secured to the base 1 and a pair of coiled springs 16 compressed between said ends and block urge said fingers to a maximum divergence. A pair of pins 17 carried by the fingers 13 and upon which said springs are coiled slide in a transverse bore 18 in the block 15 and restrain the rear ends of said fingers from movement forward and back consequently when the rear ends of said fingers are pressed toward each other, overcoming the springs 16, the joined ends of said fingers move forwardly and forwardly actuate the arm 4' and slide 3'. When said fingers are released the springs throw out the rear ends of the fingers and thus shift the arm and slide rearwardly. It is evident from Figure 3 the divergent ends of the fingers closely approach the flanks of the animal figure, so that inward pressure upon

said flanks will be transmitted to said fingers.

From the preceding description, it will be evident that the invention in either of its described forms provides a simple and inexpensive means for simulating the barking of a dog or the cry of a similar animal.

What I claim is:—

- 10 1. A sound producing device comprising a base having a rosin-treated top surface, an arm extending substantially parallel to said base, means carried by the base for reciprocating said arm upon said treated surface in substantial parallelism with the base, a flexible plate carried by said arm and bearing edgewise upon said base and a spring ex-

tending between said arm and base maintaining said plate pressed against the base.

- 20 2. A sound producing device comprising a base having a rosin-treated top surface, an arm extending substantially parallel to said base, a vibratory member carried by said arm and frictionally engaging the base, means yieldably maintaining the frictional engagement of said vibratory member with 25 the base, means carried by the base for reciprocating said arm upon said treated surface, and means upon the base for spacing said arm therefrom.

In testimony whereof I sign this specification.

CONSTANTY MAJEWICZ.
